STOVE CONTROL PANEL

George W. Walker, Detroit, Mich.

Application August 2, 1949, Serial No. 4,258

Term of patent 14 years

(Cl. D81—25)

To all whom it may concern:

Be it known that I, George W. Walker, a citizen of the United States and resident of Detroit, in the county of Wayne and State of Michigan, have invented a new, original, and ornamental Design for a Stove Control Panel, of which the following is a specification, reference being made to the accompanying drawing, forming a part thereof.

Fig. 1 is a front elevational view of a stove control panel showing my new design;

Fig. 2 is a sectional view along line 2—2 of Fig. 1.

Fig. 3 is an enlarged perspective view of a control knob removed from the panel.

I claim:

The ornamental design for a stove control panel, substantially as shown.

GEORGE W. WALKER.
